Primary Examiner — Ian Simmons*Assistant Examiner* — Carissa C Fitts(74) *Attorney, Agent, or Firm* — Saidman DesignLaw Group, LLC(57) **CLAIM**

The ornamental design for a garment, as shown and described.

DESCRIPTION

FIG. 1 is a right, rear perspective view of a garment showing my new design, the left rear perspective view being a mirror image thereof;

FIG. 2 is a front perspective view thereof; and,

FIG. 3 is a rear perspective view thereof.

The dashed broken lines illustrate unclaimed environmental structure and form no part of the claimed design. The dot-dash broken lines represent an unclaimed boundary and form no part of the claimed design.
